UNITED STATES PATENT OFFICE.

CHARLES F. SMITH, OF LOS ANGELES, CALIFORNIA.

NAIL STRIPPER.

Application filed April 15, 1926. Serial No. 102,353.

This invention relates to a nail stripper wherein nails are placed in a hopper and are caused to travel therefrom through intermediately disposed means to nail tracks 5 wherein they are aligned and assembled for withdrawal. The present invention appertains to the type of nail stripper disclosed in United States Patent 1,051,282, granted to me January 21, 1913, and more particularly to the nail tracks.

This invention contemplates a nail stripper comprising a chute from which nails disposed therein in a jumbled state slide to a runway or track, nails which are in proper 15 position entering the track with heads uppermost. The nails are retained in the track in a row ready for withdrawal by the workmen. To permit convenient and expeditious withdrawal of nails, an offset is provided 20 intermediate the chute and the far end of the track. Such offset is preferably placed at the juncture of the chute and track. It is found advantageous to vary the size of the slots in the tracks to accommodate them 25 to various sizes of nails. The primary object of this invention is to provide a novel form of nail track wherein an offset is provided which is not subject to nails becoming stuck therein and which is arranged for 30 convenient and expeditious adjustment. It is usual to have a number of tracks, and it is another object of this invention to provide means of adjustment whereby the tracks may be adjusted by a single operation.

35 These objects together with other objects and corresponding accomplishments are obtained by means of the embodiment of my invention illustrated in the accompanying drawing, in which:

40 Fig. 1 is a side elevation of a complete nail stripper; Fig. 2 is a front elevation thereof; Fig. 3 is a section as seen on the line 3—3 of Fig. 1, a portion of the chute being broken out to show the offset in a nail track; and Fig. 4 is a fragmentary view 45 showing a side elevation of the track and chute structure.

Referring more particularly to the drawing, a portable type of nail stripper is shown 50 which may be folded and housed within a case. The case comprises a body A to which a cover B is hinged. Braces are indicated as a whole by C and maintain the cover in open position, the hopper, chute and tracks in working position. The casing serves as 55 a support for a hopper D, a chute E and

tracks F, which are later described more in detail. The body A of the casing may be used to hold nails which are transferred to the hopper D and pass therefrom into the 60 chute E from which they advance into the tracks F.

The hopper is of box form, but open at the front. The rear wall thereof indicated by 5 has a bolt 6 extending therethrough and through an elongated hole in the cover B, there being a wing nut for securing the hopper to the cover. This provides for a detachable adjustable connection so that the hopper may be raised and lowered within 65 limits and detached for packing. The side walls 7 provide guards so that the hopper is in effect a chute, which, when mounted on the cover, is inclined toward the front. Thus, nails thrown upon the bottom 8 will tend to move by gravity toward the front. A brace 9 secures the body A and the cover B in open position and has intermediate its ends a number of holes. There is a brace 70 on each side of the case. Pivotally secured to the sides of the hopper are brackets 10 which may be secured by bolts 11 to the braces 9.

The chute E is of box form open at the lower end and comprises side walls and a 85 bottom. The side walls are indicated by 13 and the end wall by 14. A rod 15 extends across the chute through ears depending from the side walls 7 and through openings in the side walls 13 of the chute. This provides for a pivotal connection of the chute to the hopper at the open end of the hopper so as to receive nails which are discharged from the hopper. The bottom of the chute 90 comprises a number of parallel troughs, in 95 this instance three. Each trough comprises bottom walls 16 inclined downwardly toward open slots 17. These slots form nail slides, and are margined preferably by wire rods 18. It has been found convenient to make the chute of sheet metal and to solder the wires 18 thereto. The bottom walls are secured to the end wall 14 and are supported at the other end of the chute by suspension rods 19 which are passed through a bar 20 bridging the side walls of the chute. The nail slides each comprise a pair of parallel wires which extend to the end of the slots in the chute are turned laterally to form a swell and downwardly to form a return bend as indicated by 21 as best shown in Fig. 3. There is an S bend in each wire to a portion 100 105 110

thereof extending downwardly as indicated by 22. The wires of a slide are then directed toward each other as indicated by 23 and bent into parallel relation to form tracks. 5 In this manner the runner wires may be shaped to form an offset at the juncture of the chute and the tracks, there being a step provided with a flaring withdrawal opening. One runner of each of the tracks on the same 10 sides is secured to a support bar 25. The other wire of each runner is free of the bar 25, but secured to an adjustment rod 26. Rod 26 is threaded at one end as shown in Fig. 3 and mounted thereon is a knurled nut 27 15 disposed in a groove 28. By moving the nut upon the rod 26, the latter is moved longitudinally of the bar 25 and with it the runners on one side of each of the tracks. By turning the nut 27 the track slots may 20 be adjusted so as to accommodate them to the various sizes of nails. Bar 25 has fingers at the ends indicated by 29 which may be disposed in selected openings in braces 9, whereby the position of the bar in the braces 25 may be adjusted and thereby the inclination 25 of the chute E and runner F adjusted.

The case body A serves as a receptacle for nails. The workman picks a handful of nails from the case and drops them into the 30 hopper D. He then taps the hopper to cause the nails to slide therefrom into the chute E whereupon they roll to the bottom of the troughs, the shanks eventually passing through the slots of the slideways and the 35 heads remaining on the upper side. The

nails slide downwardly to the open end of the chute, jumping the steps and disposing themselves in the tracks with the heads up- 40 permost and in line. The nails slide downwardly in the tracks so as to fill the latter. The workman grasps a number of nails in this assembled relation in a track between his fingers and withdraws them through the step. The stripper is placed upon the work 45 bench and after the workman has started, the vibration caused by hammering will be sufficient to cause the nails to move downwardly in the hopper, chute and tracks. Some of the nails which do not right themselves will slide out of the chute and back 50 into the case. The peculiar form of the steps and offsets in the tracks, prevents nails from becoming wedged therein and thereby puncturing and cutting the hands of the workman as he reaches to grasp nails for withdrawal. 55

What I claim is:

In a nail stripper, a chute, a nail track leading from said chute and provided with a downwardly and rearwardly extending offset portion intermediate its ends and comprising a pair of spaced apart runners, and outwardly bowed portions on said runners at said offset portion of the track to permit 60 nails to be withdrawn from the track. 65

In witness that I claim the foregoing I have hereunto subscribed my name this 2nd day of April, 1926.

CHARLES F. SMITH.
